UNITED STATES PATENT OFFICE

106,973

DESIGN FOR A TUMBLER

Melvin O. Hansen, Toledo, Ohio, assignor to Libbey Glass Company, Toledo, Ohio, a corporation of Ohio

Application April 14, 1937, Serial No. 68,750

Term of patent 7 years

To all whom it may concern:

Be it known that I, Melvin O. Hansen, a citizen of the United States, residing at Toledo, in the county of Lucas and State of Ohio, have invented a new, original, and ornamental Design for a Tumbler, of which the following is a specification, reference being had to the accompanying drawing, forming a part thereof.

In the drawing:

Fig. 1 is a top plan view of a tumbler showing my new design.

Fig. 2 is a side elevational view thereof.

I claim:

The ornamental design for a tumbler substantially as shown.

MELVIN O. HANSEN.
